CLAIM

The ornamental design for a display screen with model training graphical user interface, as shown and described.

DESCRIPTION

The FIGURE is a front view of a display screen with model training graphical user interface, showing our design.

1 Claim, 1 Drawing Sheet(56)

Step 1: Training sample data generation	
Initial training case number	____
Note: All the created case parameter files are saved in '/all_initial_case/ , please check!	
Step 2: Run ToughReact to obtain all the training cases	
Note: According different operating system and hardware of your computer, this part might be a computing intensive procedure	
Step 3: Training proxy models based on neuron network	
Note: Please copy all the training cases and cases_design_parameter file to the "training_cases" folder to train proxy models. Copy blind cases to "testing_cases" folder.	
Note: Please train and select model save path.	
Training data percentage	____
Validate data percentage	____
Test data percentage	____
Train Dolomite Proxy	☐
Train Porosity Proxy	☐
Train Permeability Proxy	☐
Train pH Proxy	☐
Train HCO3- Proxy	☐
Train Ca+2 Proxy	☐
Train Mg+2 Proxy	☐
Step 4: Blind test with fitted proxy model	
Blind test case index	____
Note: Please run and select model load path.	
Run Dolomite Test	☐
Run Porosity Test	☐
Run Permeability Test	☐
Run pH Test	☐
Run HCO3- Test	☐
Run Ca+2 Test	☐
Run Mg+2 Test	☐
Step 5: Do prediction with the fitted proxy model with given parameters	
Permeability of the initial model	____
RSA of the Model	____
Injection rate of the model	____
Close all plot windows	☐
Run prediction with proxy	☐
Run Simulation for Comparison	☐
